UNITED STATES PATENT OFFICE

137,224

DESIGN FOR A BADGE

Harry E. Houghton, New York, N. Y., and Lucinda Crile, Washington, D. C., assignors to the United States of America, as represented by Marvin Jones, administrator of the War Food Administration, and his successors in office

Application October 16, 1943, Serial No. 111,404

Term of patent 3½ years

To all whom it may concern:

Be it known that we, Harry E. Houghton, a citizen of the Dominion of Canada, residing at 912 Fifth Avenue, New York, New York, and Lucinda Crile, a citizen of the United States and an employee of the United States Department of Agriculture, residing at Roosevelt Hotel, Washington, D. C., whose post-office addresses are 1/2 United States Department of Agriculture, Washington, D. C., have invented a new, original, and ornamental Design for Badges, of which the following is a specification, reference being had to the accompanying drawing, forming part thereof.

Fig. 1 in the drawing referred to is a plan view and Fig. 2 is an edge view of a badge showing our new design.

We claim:

The ornamental design for a badge as shown.

HARRY E. HOUGHTON.
LUCINDA CRILE.
